CLOSURE FASTENER FOR CONTAINERS

William H. Inman, Newark, N. Y., assignor to
 Bloomer Bros. Company, Newark, N. Y., a corporation of New York

Application December 10, 1941, Serial No. 422,385

2 Claims. (Cl. 229—26)

This invention relates to a closure fastening for a container made of fibrous sheet material of the general form commonly known as an oyster pail. The primary object of the invention is the provision of a simple and effective closure fastener so designed and constructed as to require no metal parts.

Another object is the provision of a non-metallic closure fastener of such form that it can be closed with a minimum of effort on the part of the user and, when closed, will hold the closure parts effectively and tightly in closed position.

A further object is the provision of such a closure fastener so designed and constructed that it does not appreciably increase the cost of manufacture of the container on which it is used.

To these and other ends the invention resides in certain improvements and combinations of parts, all as will be hereinafter more fully described, the novel features being pointed out in the claims at the end of the specification.

In the drawing:

Fig. 1 is a plan of a flat blank of fibrous sheet material from which may be constructed a container embodying the closure fastener of the present invention;

Fig. 2 is a perspective view of the completed container with the closure flaps in open position;

Fig. 3 is a similar view with the closure flaps in closed position and held in such position by the fastener of the present invention;

Fig. 4 is a vertical section through a fragment of the closed container, the section being taken centrally through the fastener parts, and

Figs. 5 and 6 are plans of a tab portion and eye portion, respectively, constituting the fastening means of the present invention.

The same reference numerals throughout the several views indicate the same parts.

Referring first to Fig. 1, the blank from which the container is made may be of the conventional fiber board, cardboard, or fibrous sheet material stock, commonly known as carton stock, and except for the closure fastening means hereinafter described the rest of the carton itself may be of the conventional form commonly employed in a so-called "oyster pail," including, for example, a rectangular bottom section 11, hinged to opposite edges of which are tapered side walls 13 and 15 to the upper edges of which inner closure flaps 17 and 19, respectively, are hinged. To the other opposite edges of the bottom section are hinged tapered side walls 23 and 25 to the upper edges of which outer closure flaps 27 and 29, respectively, are hinged. Corner fold sections of the usual kind are employed, such as the fold sections 31 and 32 between the side walls 13 and 25, the fold sections 33 and 34 between the side walls 25 and 15, the fold sections 35 and 36 between the side walls 15 and 23, and the fold

sections 37 and 38 between the side walls 23 and 13. These parts are all folded up in conventional manner, to form the complete oyster pail as shown in Figs. 2 and 3, of conventional form except for the closure fastener hereinafter described.

In the erected pail, the corner fold sections 31 and 32 are folded flat against each other and the sections 33 and 34 are folded flat against each other, and these two pairs of sections are folded, in somewhat overlapping relation to each other, against the outer side of the side wall 25. Likewise the corner fold sections 35 and 36 are folded flat against each other, and the fold sections 37 and 38 are folded flat against each other, and these two pairs of sections are folded, in somewhat overlapping relation to each other, against the outer side of the side wall section 23, with the sections 37, 38 preferably lying outside of the sections 35, 36. A wire bail handle 41 is inserted at one end through the folded sections 31, 32, 33, and 34 where they overlap each other, and clinched over inside these sections, which serves to hold them in the intended overlapping position, and at its other end the wire bail is inserted through the folded sections 35, 36, 37, and 38 where they overlap each other, and similarly clinched over, likewise holding them in the intended folded position, in addition to serving as a convenient handle for the entire container.

To close the open top of the container after it has been filled with oysters or other products, the inner pair of closure flaps 17 and 19 are first folded down across the mouth of the container and in overlapping relation to each other, and then the outer pair of closure flaps 27 and 29 are likewise folded down in overlapping relation to each other and in overlying relation to the flaps 17 and 19.

The closure flap fastening means of the present invention comprises an eye or opening formed in the fibrous carton stock adjacent one edge of the mouth of the container, and a tongue or projection at one edge of the uppermost closure flap 29, which tongue or projection may be thrust through the eye or opening and so manipulated as to be retained therein, for purposes of holding the uppermost closure flap in its folded-down or closed position, thus also retaining in closed position the three closure flaps beneath.

The eye or opening is formed by holes 51 and 52 in tabs or projections 53 and 54 extending upwardly from the upper edges of the corner fold sections 37 and 38, respectively, in such position that when these sections 37 and 38 are folded into normal position, the projections 53 and 54 will lie in overlapping relation to each other and the holes 51 and 52 will be substantially aligned with each other, to constitute, in effect, a single eye or opening through the two thicknesses of

material. This eye or opening, as best seen in Fig. 6, is of approximately trapezoidal shape, narrower at the top than at the bottom, and is so placed in the material that the lower edge of the opening is preferably at or slightly below the level of the upper edges of the side walls of the oyster pail.

The tongue or projection which enters the opening 51, 52 to hold the closure in closed position, is formed on the free end of the outermost closure flap 29, as an integral extension 61 thereof, partially separated from the main body of the flap 29 by cuts 63 extending inwardly from opposite lateral edges, and by short terminal cuts 65 extending from the inner ends of the cuts 63 in directions at right angles thereto toward the extreme outer end of the tab 61.

The tab 61, after being cut in this manner is of somewhat arrowhead shape, as best shown in Fig. 5, and includes a tapered forward end integrally connected to the closure flap 29 by the material or shank lying between the two cuts 65, and having rear corners 67 which may readily be bent out of the plane of the main projection 61, due to the weakening effect of the cuts 63 and 65. The width of the uncut portion between the two slits 65 is preferably substantially the same as the width of the narrow upper part of the eye 51, 52. The pointed forward end of the projection 61 is narrower than the width of the upper part of the eye, while the broad rear end of the tab 61 (including the wings 67) is wider than the widest part (the lower part) of the eye. This relation of the parts is readily seen from a comparison of Figs. 5 and 6.

In use, the oyster pail is filled when the parts are in the relative positions indicated in Fig. 2. Then the inner pair of closure flaps 17 and 19 are folded down across the top or mouth of the pail. The closure flap 27 is folded down across the flap 17 and 19 at right angles thereto, and finally the closure flap 29 is folded down on top of the flap 27. As the flap 29 comes down, the end of the tab 61 is thrust through the eye 51, 52 and the projecting end beyond the eye is grasped and pulled upwardly with a quick sharp motion. This serves to bend the material 53, 54 (in which the eye 51, 52 is formed) inwardly to a position such as shown in Fig. 4, and at the same time to deform the wings 67 of the tab 61 sufficiently so that they will pass through the eye 51, 52. The upward pull on the tab 61 elevates that part of the tab which projects through the eye up to the narrower upper part of the eye, where the tab is more securely held. The wings 67, which meanwhile have passed through the eye, are bent downwardly by this upward motion of the rest of the tab, and assume a position with the rear edges of the wings 67 resting on the front surface of the material 54 around the eye, as indicated somewhat diagrammatically in Figs. 3 and 4.

This completes the closure of the oyster pail in a most effective and satisfactory manner, holding the closure flaps tightly closed against accidental opening from the jars and other conditions customarily encountered in transporting the full pail. However, if the pail is provided with the wire bail handle 41, as is preferably the case, the handle is swung upwardly to an upstanding position as shown in Figs. 3 and 4, and as it comes upwardly it will produce a camming action on the inclined lateral edge of the tab 61, camming this tab upwardly and inwardly until the flat end of the tab rests against and is held

up by the bail handle when the latter is in its completely upstanding position as shown. Thus the handle gives additional protection against accidental disengagement of the parts.

When the pail is to be opened, it is a simple matter to swing the bail handle aside, then grasp the projecting end of the tab 61 and swing it downwardly approximately to a horizontal position, at the same time grasping the top edge of the layers 53, 54 and swinging them outwardly to a position somewhat outwardly beyond a vertical position, which motion readily causes the tab 61 to be drawn back through the wide lower part of the eye so that the closure flaps of the pail may be opened to obtain access to the contents.

While one embodiment of the invention has been disclosed, it is to be understood that the inventive idea may be carried out in a number of ways. This application is therefore not to be limited to the precise details described, but is intended to cover all variations and modifications thereof falling within the scope of the appended claims.

I claim:

1. A closure fastening means for a carton of the type formed from a single sheet of flexible material cut, scored and folded to provide a bottom, side walls including corner folds, and a top closure, said fastening means comprising a portion of said corner folds extended above the carton top at one side thereof and having an opening formed therein adjacent said top, a tab projecting integrally from the edge of said closure, said tab having tapered sides converging outwardly to a width less than that of said opening so as to be readily inserted therethrough and to extend beyond the lateral outlines of said carton side walls, but being wider at its inner end than said opening, with undercut inner corners adapted to engage the outer face of said corner fold portion on opposite sides of said opening, and a handle extending in a loop over said closure with its ends secured to said corner folds on opposite sides of said carton, said handle being adapted to engage the tapered sides of said tab and bend said tab upwardly against the upper side of said opening and within the lateral outlines of said carton side walls.

2. A closure fastening means for a carton of the type formed from a single sheet of flexible material cut, scored and folded to provide a bottom, side walls including corner folds, and a top closure, said fastening means comprising a portion of said corner folds extended above the carton top at one side thereof and having therein a tapered opening of substantial height, narrower at its top than at its bottom, a tab projecting integrally from the edge of said closure and having tapered sides converging outwardly to a width less than that of the bottom of said opening so as to be readily inserted therein and to extend beyond the lateral outlines of said carton side walls, said tab being wider at its inner end than the greatest width of said opening, with undercut inner corners adapted to engage the outer face of said corner fold portion on opposite sides of said opening, and a handle extending in a loop over said closure with its ends secured to said corner folds on opposite sides of said carton, said handle being adapted to engage the tapered sides of said tab and bend the same upwardly within the lateral outlines of said carton side walls and interlock its inner corners with the narrower top portion of said opening.
